CAN POURING APPLIANCE.

Original Filed June 17, 1935

FIG. 2.

INVENTOR

WILLIAM A. MILLER,
By: John D. Ringer,
his Atty.

UNITED STATES PATENT OFFICE

2,056,530

CAN POURING APPLIANCE

William A. Miller, Monterey Park, Calif., assignor
of one-half to Wayland H. Crawford, Alham-
bra, Calif.

Application June 17, 1935, Serial No. 26,914
Renewed July 1, 1936

1 Claim. (Cl. 221—23)

This invention relates to devices used for punching sealed cans for drawing liquids therefrom by means of suitably shaped parts of the devices.

5 One of the objects of this invention is to provide a device that can be applied by quick lever action to make it ready for the pouring.

Another object is to provide means whereby air will be shut off automatically by action of the spring that controls the pouring or spout shutter.

Another object is to provide a device so designed that it will stay clamped to a can by the very movements in pouring liquids from the can.

Another object is to provide a simplified structure that is at the same time sturdy and easily handled.

Other objects will appear from the following description and appended claims as well as from the accompanying drawing, in which—

Fig. 1 is a fragmentary vertical section through the device in a position as it appears when applied over the top of a can, showing also in dotted lines the position of the handle for and preparatory to clamping the device to a can, and also the position of the discharge mechanism in open position in dotted lines.

Fig. 2 is a fragmentary side elevation partly broken away of a slightly modified form.

As illustrated, a cross bar 3 serves as a support or mounting for the other parts of the device, at the same time having the hook-end 4, to engage over one side of a can while the bar is placed over the top of the can. The opposite end 5 is provided with lugs 6 with a pivot 7, by which the handle 8 is swingably mounted on the bar 3 for engaging over the opposite side of the can.

At the end 4 there is a spout 9, extending outwardly from the bar 3, and from the spout extends a conduit or passage 10 provided in a pointed punching member 11, of which the pointed end projects inwardly.

The pointed member 11 is so designed that a can, when placed sidewise against the member 11, can be punched at such a side by means of lever action on the handle 8 forcing the can towards and over the member 11.

A lever-end 12 is provided on the handle 8 and the lever-end is designed with a shouldered portion 13, adapted to engage over the opposite side of the can and so that, when the handle is pressed downwardly, the engaged can is tilted upwardly, first, so as to cause the punching of the opposite side by the member 11, and, as the can moves

further upwardly, so as to cause a punching of the top of the can for an air-vent.

From the bar 3 projects for this purpose a second punching member 14 with a pointed end poised so that it will force itself into the top 5 of the can as the can is moved into its proper pouring position, this member 14 being also provided with a passage, indicated at 15, extending upwardly through the bar 3, forming the air-vent. 10

A control lever 16 is pivotally on the top of the bar 3 having at one end a closing member or portion 17 to fit snugly over the spout 9 for keeping the spout and thereby any attached can sealed when not handled for pouring purposes and having at the other end a handle member 18. 15

For keeping the control device in a closed position, a spring 19 is firmly secured to the underside of the handle member 18 and the spring is formed so as to come with its end portion 20 to 20 rest over the passage 15 in normal closing position.

When a pouring is desired from a can held in this device, the handle member 18 is pressed downwardly against the tension of the spring 19 25 so as to lift the closing member 17 to the position indicated in dotted lines at 17a, freeing the spout 9, at the same time the spring 19 is compressed to bring the end 20 to an upwardly tilted position indicated at 20a, so that air can enter 30 through the passage 15 that is thereby made free at the same time when liquid is drawn from the spout 9 through the hollow punching member 11.

The air-vent 15 is automatically closed by the spring returning to its normal position when the handle 18 is released for closing the spout 9 by the member 17. 35

8a indicates the position of the lever 8 when in the position for catching a can for forcing the can to be punched and moved into engaged position, a portion of a can being indicated at 21 in a position preparatory to being forced against the punching members and preparatory to being moved into engaged position, the engaged position of the can being indicated in dash-dotted 45 lines at 21a.

In Fig. 2, a slightly modified form is illustrated, especially suitable with cans that are commonly fully emptied after once being punctured or opened, as, for instance, with sealed oil cans; 50 while the device illustrated is preferably used with cans that are emptied from time to time, such as milk cans.

In this modified form, the cross bar 22 is preferably made of heavy steel with a hook-end 23, 55

provided with a suitably long tube 24. The opposite end 27 is provided with pivot 26. A handle 25 is swingably mounted in a similar manner as with the device illustrated in Fig. 1.

6 Being of steel, the punching member 28 is readily stamped out of the material of this bar, as will easily be understood from the illustration.

In application, this device is handled in a similar manner as described with reference to Fig. 1.

10 A can is first applied in a tilted position to be

caught on the punching end of the tube 24 and is

then forced upwardly until the top of the inserted

can is punctured by the punching member 28. A

15 tearing of a hole for the air-vent is all that is

necessary with cans that are to be handled with

this device, while with the device of Fig. 1 suitable

sealing around the punching members can

readily be provided for, as will readily be under-

stood from the illustration.

20 Having thus described my invention, I claim:

In a can appliance of the class described, a

member forming a support and designed to rest

over the top of a can having a portion extending

downwardly from one end for engaging over one

25 side of the inserted can and having a pivoted

member at the opposite end for engaging the

opposite side of said can, a punching member disposed in the first-named end poised to puncture the adjacent side of the inserted can and having a passage extending outwardly, a handle swingably mounted on the pivoted member and having a lever portion to engage over the opposite side of the can and designed to force the can against the punching member and move the can into pouring position, a second punching member in the support having the punching end extending downwardly so as to become effective when the can is forced into pouring position and being provided with a passage, and a control device swingably mounted on the top of the support with one end formed as a closing member for the 15 first-named passage and the other end formed as a handle, and a spring disposed between the handle and the second-named punching member so as to rest on the second-named passage for closing this when the device is in closing position, the spring being designed and arranged so that it automatically tilts so as to free the second-named passage for an air-vent when the spout control device is moved to the pouring or open position.

25

WILLIAM A. MILLER.
